RECEPTACLE WITH PICTURE DISPLAY

William F. Bowen, North Attleboro, Mass., assignor to Evans Case Company, North Attleboro, Mass., a corporation of Massachusetts

Application January 21, 1938, Serial No. 186,211

9 Claims. (C.I. 40—156)

The invention relates to receptacles generally, but may be particularly adapted to compacts, cigarette cases, combination cigarette case, lighter and compact, and other receptacles for personal use especially such as are adapted to be carried on the person in a pocket or a bag.

It is a purpose of the present invention to provide in such a receptacle a frame or locket-like device in which may be displayed a picture or insignia or the like. In one form the invention may take it is possible to display two pictures, insignia or the like, one of which is visible from the outside when the receptacle is closed and the other is visible from the inside when the receptacle is open. The frame or locket may be hinged so as to be adjustable or movable in the receptacle member to which it is attached. Means may be provided for removing and replacing the contents of the locket so that different pictures or insignia may be substituted from time to time or when desirable. Preferably means are provided to hold the locket in position for display. The locket may be associated with a frame or collar into which it fits more or less neatly and which may assist in holding in position the portion of the locket which may be removed for changing the material to be displayed.

In such a receptacle it may be convenient to put the frame or locket-like device into one member of the receptacle so as to be accessible and visible from the outside. It is immaterial which member of the receptacle is so used but for purposes of illustration and description the frame is illustrated as attached to the cover of the receptacle. The term cover, however, is not employed in a limiting sense. It is to be understood that as here used the term cover is merely used as a convenient means for describing one member of a receptacle and may signify any member of a receptacle to which the frame or locket is applied.

In the accompanying drawing is illustrated one specific embodiment of the invention. Figure 1 is a top plan view of a closed receptacle provided with the new picture display frame. Fig. 2 is a plan view similar to Fig. 1 with the cover opened. Fig. 3 is a transverse vertical section on the line 3—3 of Fig. 2 dotted lines being employed to indicate a position to which the frame may be moved. Fig. 4 is a fragmentary vertical section on the line 4—4 of Fig. 3. Fig. 5 is a fragmentary vertical section on the line 5—5 of Fig. 3. Fig. 6 is a fragmentary transverse horizontal section on the line 6—6 of Fig. 2, the frame or locket being shown empty. Fig. 7 is a perspec-

tive view of the portion of the frame or locket which may be removed to allow access to the interior of the frame.

The particular structure illustrated in the drawing is a compact having a base or bottom 10 of standard construction. Hinged to this is the other member of the receptacle which will hereinafter be referred to as the cover 11. The cover 11 may carry a mirror 12 which may be held in place by a lining member 13 which has an appropriate aperture for the mirror 12. The cover 11 has appropriately located an opening 14 which may be provided with an ornamental or reinforcing border 15. In the lining 13 is an opening 16 registering with the opening 14 in the cover 11. Surrounding the opening 16 is a raised collar 17.

The collar 17 is provided with a hinge mechanism 18 carrying a frame 19 which may be substantially the same size as the holes 14 and 16. The frame 19 is preferably so carried that one surface will, in closed position, be at substantially the level of the border 15. When the frame 14 is in closed position indicated in full lines throughout the drawing it lies within the collar 17. At its side opposite the hinge 18 the frame 14 may be provided with a suitable catch mechanism indicated as overturned lugs 20 to engage upset portions 21 in the collar 17 to hold the frame in position in the collar. The frame 19 has apertured face members 22 and 23 through which may be displayed pictures, insignia or the like 24 and 25 when the frame is filled. Underlying the face members 22 and 23 may be sheets of suitable transparent material 26 and 27 such as glass, celluloid, celotex, etc., against which may lie pictures, insignia or the like 24 and 25. A filling block 28 may be inserted between these so as to hold the material to be displayed against the transparent plates 26, 27 or against the face members 22 and 23 if the transparent plates are omitted. Preferably the top, bottom and one side of the frame 19 will be integral with the face members 22 and 23, being stamped or welded or soldered or otherwise attached thereto. This leaves one side of the frame open and when the frame is turned on its hinge 18 to the position indicated in dotted lines in Figs. 3 and 4 the contents of the frame 19 may be supplied, removed or changed.

In order to hold the contents in the frame 19 there may be provided a U-shaped member 29 to fill the open side of the frame 19. The arms 30 and 31 of the U-shaped member 29 when in position lie closely against the top and bottom mem-

- bers of the frame 19. The arms 30 and 31 may be provided with lugs 32 to engage corresponding openings 33 in the top and bottom members of the frame 19 so as to open the locket or hold the member 29 in position. It will be noted that the member 29 will lie more or less snugly against one side of the collar 17 when the frame 19 is in the position indicated in full lines in the drawing. Thus the member 29 will tend to be held in position by the collar 17.

When desired the face member 22 may have an outwardly extending lip 34 to rest against the edge of the collar 17 and form a neat cover for the closure. The member 29 when in position may lie under and closely engage the edges of the face members 22 and 23. When the frame member 19 is in the position indicated in dotted lines any suitable mechanism such as an awl, needle or the like may be inserted through the hole 33 to engage the lugs 32 or the arms 30 or 31 and force the member 29 outward. When it has been forced beyond the edge of the face plate 23 the member 29 itself may be engaged by the finger or by any suitable tool and thus withdrawn from the frame member 19 to allow insertion, rearrangement or substitution of the contents of the frame member 19.

While pictures 24 and 25 have been illustrated as suitable display contents for the frame 19 any desired material may be thus displayed and either or both sides may be left blank without any display material or may contain material which augments, contrasts with or harmonizes with the surface ornamentation of the receptacle or of the lining.

The invention may be embodied in other forms which may vary in detail, construction, arrangement and location from the specific embodiment illustrated.

40 4. I claim as my invention:

1. In a receptacle a cover having a hole therein, a lining for the cover having a hole registering with the hole in the cover, a collar about the hole in the lining, a frame open at one side and provided with display openings at its front and back and registering with the holes, a hinge connection between the collar and the frame, means on the frame engaging the collar to hold the frame in the collar, a U-shaped member closing the open side of the frame with the arms of the U extending into the frame, and means on the arms of the U-shaped member to engage the frame and hold it in place.

2. In a receptacle a cover having a hole therein, a lining for the cover having a hole regis-

tering with the hole in the cover, a collar about the hole in the lining, a frame registering with the holes and a hinge connection between the collar and the frame.

3. In a receptacle a cover having a hole therein, a lining for the cover having a hole registering with the hole in the cover, a collar about the hole in the lining, a frame registering with the holes, a hinge connection between the collar and the frame and means on the frame engaging the collar to hold the frame in the collar. 5

4. In a receptacle a cover, a lining for the cover, a collar on the lining, a frame open at one side, a hinge connection between the collar and the frame, means on the lining engaging the frame to hold the frame in the collar, a U-shaped member closing the open side of the frame with the arms of the U extending into the frame, and means on the arms of the U-shaped member to engage the frame and hold it in place. 10

5. A frame open at one side and provided with display openings at its front and back, a U-shaped member closing the open side of the frame with the arms of the U extending into the frame, and means on the arms of the U-shaped member to 15 engage the frame and hold it in place. 20

6. In a receptacle a cover having a hole therein, a lining for the cover, a collar on the lining, a frame open at one side and registering with the hole, a hinge connection between the collar 30 and the frame, means on the frame engaging the collar to hold the frame in the collar, a U-shaped member closing the open side of the frame with the arms of the U extending into the frame and means on the arms of the U-shaped member to 35 engage the frame and hold it in place.

7. In a receptacle a cover having a hole therein, a lining for the cover, a frame open at one side and registering with the hole, a member for closing the open side of the frame and means 40 carried by the lining for holding the closing member in place when in register with the hole.

8. In a receptacle a cover having a hole therein, a frame mounted on the cover and open at one side and registering with the hole, a member for closing the open side of the frame, and means carried by the cover for holding the closing member in place when in register with the hole. 45

9. A frame open at front and back and open 50 at one side, a U-shaped member closing the open side with the arms of the U extending into the frame, and raised lugs on the arms interlocking with holes in the frame.

WILLIAM F. BOWEN. 55
